UNITED STATES PATENT OFFICE.

FAYETTE WILLIAM KEELER, OF TEMPLE, TEXAS, ASSIGNOR OF ONE-HALF TO W. MORANTS,
OF TEMPLE, TEXAS.

MEANS FOR AUTOMATICALLY CLOSING ELECTRIC CIRCUITS.

No. 879,648.

Specification of Letters Patent.

Patented Feb. 18, 1908.

Application filed August 18, 1906. Serial No. 331,216.

To all whom it may concern:

Be it known that I, FAYETTE WILLIAM KEELER, citizen of the United States, residing at Temple, in the county of Bell and 5 State of Texas, have invented certain new and useful Improvements in Means for Automatically Closing Electric Circuits, of which the following is a specification.

The present invention is essentially advantageous for railways or systems operating but a single wire since it will automatically close the circuit if opened at any one or more stations in the time specified, thereby saving considerable annoyance and delay. Moreover, it also enables the train dispatcher to communicate with all the operators at once, if needs be, as well as to awaken those who are unfortunate enough to be asleep.

For a full description of the invention and 20 the merits thereof and also to acquire a knowledge of the details of construction of the means for effecting the result, reference is to be had to the following description and accompanying drawings.

25 While the invention may be adapted to different forms and conditions by changes in the structure and minor details without departing from the spirit or essential features thereof, still the preferred embodiment is 30 shown in the accompanying drawings, in which:

Figure 1 is a diagrammatic view. Fig. 2 is a detail view of a series of circuits to be closed at one time. Fig. 3 is a detail view of 35 the circuit closer for the bell circuit.

Corresponding and like parts are referred to in the following description and indicated in all the views of the drawings by the same reference characters.

40 The numeral 1 indicates a clock movement of ordinary construction adapted to be operated by a spring 2, which is adapted to be wound in the usual manner. The train of gearing may embody any number of elements 45 and comprises an arbor 3 provided with a disk 4, the gearing comprising the train being so proportioned as to drive the arbor 3 and disk 4 at any required rate of speed. A driver is loosely mounted upon the outer end 50 of the arbor 3 and is approximately of cap-form, consisting of a sleeve 5 and an annulus or plate 6, the latter adapted to make fric-

tional engagement with the disk 4. A bearing point 7 is provided at the outer end of the driver or sleeve portion thereof and is adapted to receive the thrust of a lever 8 pivoted at 9 and adapted to operate between stops 10 and 11. A pointer 12 is connected with the driver or sleeve so as to rotate therewith when the plate or part 6 is in frictional contact with the disk 4. An adjustable contact 13 is arranged in the path of the pointer 12 and forms one terminal of a bell circuit, the pointer 12 constituting the other terminal of said circuit. The bell is indicated at 14, and 15 and 16 are wires leading therefrom to the parts 12 and 13, a battery 17 being interposed in the length of the wire 16. Normally, the parts 12 and 13 are out of contact and upon application of pressure to the point 7 through the lever 8, the parts 4 and 6 are brought into engagement and the driver caused to rotate with the part 4, whereby the pointer 12 is carried around and brought into contact with the part 13, closing the bell 75 circuit and sounding an alarm. The lever 8 is normally acted upon by a retractile spring 18 and is provided with an armature 19 which co-operates with the core of an electro-magnet 20 included in a circuit with the local 80 sounder 21.

The circuit includes wires 22 and 23, the local battery 24 being interposed in the wire 22. An armature 25 constitutes one terminal of the local circuit and a contact 26 forms 85 the other terminal and when the local circuit is closed, as when the parts are in normal position, the armatures of the local sounder and the electro-magnet 20 are attracted, thereby holding the lever 8 away 90 from the point 7 of the driver and permitting continuous movement of the train of gearing without imparting motion to the pointer 12, whereby the alarm circuit remains open. The armature 25 is spring actuated and 95 forms part of a relay which includes an electro-magnet 27 which is included in the main line wires 28 and 29. The circuit closing key 30 may be of any construction depending upon the particular adaptation of 100 the invention, and enables opening and closing of the main line in the accustomed manner to transmit a message. Shunt wires 31 and 32 are looped into the main line and con-

nect therewith upon opposite sides of the key 30. The shunt circuit is adapted to be closed at 33 upon opening the main line circuit by the key 30 in the manner presently to be explained.

- The bell circuit, as also the circuits of the several instruments, are adapted to be closed at 34, which represents two series of contacts normally separate, but which are brought 10 into electrical connection to close the several circuits at or about the instant the alarm circuit is closed. One set of contacts is carried by a strip 35 which is supported in normal position by means of a lug 36 on the arm 37 15 of the bell hammer and which arm, when moved towards the bell, withdraws the lug 36 from beneath the strip 35 and permits the same to move and bring the two sets of contacts into engagement.
- 20 It will be observed that the alarm circuit is first closed at 12 and 13 and is subsequently short circuited at 34, thereby permitting continuous ringing of the bell even though the contact points 12 and 13 should 25 separate to again open the bell circuit. At about the same instant that the bell or alarm circuit is closed at 34, the main circuit is closed and energizes the electro-magnet 27 of the relay and attracts its armature 25, 30 thereby closing the local circuit and energizing the electro-magnet 20 which attracts its armature 19 and one end of the lever 8 so as to release the pressure upon the point 7, 35 whereby the pointer 12 returns to normal position.

It is to be understood that the pointer 12 is weighted at its lower end and normally hangs perpendicular and its movement is such with relation to the distance of the contact 40 13 therefrom that a minute or a minute and a half must elapse before the two contacts 12 and 13 come together after the pointer begins its movement.

Provision is had to automatically close the 45 main circuit when the clock movement has about run down, this being effected by means of a spring contact 38 arranged in the path of the spring 2 and a contact 39. A wire 40 connects the spring contact 38 with the shunt wire 32, and a wire 41 connects the contact 39 with the shunt wire 31. The spring contact 38 is arranged in the path of the spring 2 to be pressed upon thereby 50 when said spring 2 is nearly or quite run down to cause the contacts 38 and 39 to come together and close the circuit. It is to be understood that the spring 2 is of the spiral type and expands as it unwinds or runs down, the contacts 38 and 39 being so arranged 55 as to be brought in electrical connection at the prescribed moment.

Operation: The parts being disposed substantially as herein disclosed when the main line is open, as for instance by means of the

key 30, the armature 25 of the relay is moved 65 away from the core of the electro-magnet 27 by the action of the spring 42, thereby breaking the local circuit, including the electro-magnet 20 and 21. The instant the electro-magnet 20 is deenergized, the lever 8 is 70 moved by the spring 18 to carry the armature 19 away from said electro-magnet and against the stop 11, thereby causing the opposite end of said lever 8 to press upon the point 7 which brings the parts 4 and 6 in contact, whereby the pointer 12 is turned until it comes in contact with the part 13, thereby 75 closing the alarm or bell circuit. When the arm 37 is moved at its free end towards the bell, the lug 36 is withdrawn from the strip 80 35, thereby permitting short circuiting of the alarm circuit at 34 and insuring continuous ringing. The action of the arm 37 also releases one or more main line contact points to suit conditions, as indicated in Fig. 2. 85 After all the instruments connected with the contact points shown in Fig. 2 have been short-circuited, the circuit is established in the main line wire that is open, thereby closing the local circuit which energizing the 90 electro-magnet 20 attracts the armature 19, and moves the lever 8 away from the driver, and the pointer 12 being free assumes a normal position by gravitational force or other manner that may be determined upon. As 95 the pointer 12 assumes a normal position, the bell or alarm circuit is broken at 12 and 13, but the bell continues to ring because short-circuited at 34. The attention of the attendant being attracted by the ringing of 100 the bell, examines the connection of all the instruments and if any be found defective, the same is corrected, the bell circuit and all the instruments being cut in by movement of the strip 35 and engaging the same with 105 the lug 36 in the manner heretofore stated. The strip 35 may be of any material and construction and the contacts attached thereto are electrically insulated, whereas the complementary contacts are correspondingly 110 placed and electrically insulated. One set of contacts, only, are included in the bell or alarm circuit, whereas corresponding contacts of the series are electrically connected with circuits of the respective instruments 115 of a building, station or other locality or system. Each office, station or point is similarly equipped and in the case of a railroad the devices are placed on the train despatcher's wire, and as the armature in all of the 120 devices move in unison it is readily understood that when an open circuit is made on said wire that all the bells will ring. As heretofore stated, the contact point 13 is placed at such a distance from the pointer 12 so that 125 a definite period of time will elapse before the contacts 12 and 13 are electrically connected, as for instance, one minute or one

minute and a half. The interval of time can be varied by moving the contact point 13 with reference to the pointer 12. If any other wire be opened, if a short circuit drops 5 or contacts, as shown in Fig. 2, all that is necessary to do to effect closing the same is to open the train wire until the pointer 12 makes electrical connection with the contact 13, which will close the bell or alarm circuit 10 and allow all the circuits, which includes the one which is opened, to become short-circuited at 34, whereby all the instruments are again cut into circuit.

From the foregoing it will be understood 15 that the circuit closing means may be installed at comparatively small cost, is positive in action and can be connected with the local sounder circuit. On railroads or other systems operating a single wire, this is of 20 great advantage, as it will close the wire if opened at any one or more stations in the time specified, saving considerable annoyance and delay, besides enabling the train despatcher to communicate or signal all the 25 operators at once, should it become necessary as well as to awaken any who had fallen asleep. When the clock movement is nearly or quite run down, the instrument is short-circuited and cannot be operated until 30 the spring 2 is wound. This insures the instrument being kept wound, otherwise it will be useless, because cut out of action through shunt wires 31 and 32, and by the wires 40-41 and the contacts 38 and 39.

35 The above described apparatus is installed at each of the several stations on the main line circuit constituted by the wires 28 and 29 and forms a means for preventing the main circuit from being interrupted at any 40 one of the stations for a longer time than that required for the pointer 12 to make contact with the member 43, without the sounding of an alarm. Owing to the fact that it takes an appreciable length of time such as a 45 minute and a half or two minutes as previously mentioned for the pointer to reach the contact 13, the short breaks in the circuit required in transmitting a message may be made without throwing the alarm mechanism into operation. It will thus be apparent that while the main line circuit can be broken for short lengths of time in receiving or transmitting a message, it can not be 50 permanently interrupted without sounding an alarm at each of the stations and causing the different operators or attendants to inspect all connections to locate and remedy the trouble.

Having thus described the invention, what 55 is claimed as new is:

1. In combination, an alarm circuit, a local circuit including an electro-magnet and adapted to be opened and closed, a lever actuated by the magnetizing and the de-

magnetizing of said electro-magnet of the 65 local circuit, and circuit closing means for the alarm circuit adapted to be operated by said lever, the same consisting of a rotary member, a complemental member brought into operative relation therewith upon movement of the said lever in one direction, a contact carried by said complemental member and included in the alarm circuit, and a second contact likewise included in said alarm circuit. 75

2. In combination, an alarm circuit, a local circuit including an electro-magnet and coöperating lever provided with an armature, said local circuit adapted to be opened and closed, and circuit closing means for the 80 alarm circuit adapted to be controlled by means of the aforesaid lever and comprising a rotary member and a complemental member adapted to be brought into contact with said rotary member by the action of the aforesaid lever. 85

3. In combination, an alarm circuit including coöperating contacts, one of said contacts being movable, a rotary member, a complemental member adapted to be brought 90 into contact with the rotary member and provided with said movable contact members, a lever adapted to effect engagement of the rotary and complemental members, and an electric circuit including an electro- 95 magnet arranged to effect movement of the said lever.

4. In combination, a main circuit, a secondary circuit including contacts, a clock movement as means for bringing said contacts of the secondary circuit into engagement, and a cut out circuit having contacts arranged with reference to the clock movement to be actuated thereby when said movement is nearly or quite run down to effect 100 cutting of the instrument out of circuit when the clock movement is nearly or quite run down. 105

5. In combination, an alarm circuit, a clock movement, electrically actuated means 110 for effecting a closing of the alarm circuit by conjoint coöperation, and contacts for short circuiting the alarm circuit by inward movement of the hammer thereof, whereby said alarm circuit will continue to sound after 115 the primary actuating means have been restored to normal condition.

6. In combination, an alarm circuit including a fixed and a movable contact, a rotary member, a complemental member 120 carrying said movable contact, a local circuit including an electro-magnet and circuit closing means, a lever actuated by said electro-magnet and adapted to bring the rotary member and its coöperating complemental member into coöperative engagement, a main line including a relay for actuating the circuit closing means of said local 125

circuit, a shunt circuit looped into the main line, circuit closing means for the shunt circuit brought into coöperation when the actuating means for the aforesaid rotary member 5 have nearly or quite spent their force, and short circuiting means for the alarm circuit normally held open by the alarm but permitted to come into play upon inward movement of the alarm, whereby the latter con-

tinuously sounds until the parts are read- 10 justed by the attendant.

In testimony whereof I affix my signature in presence of two witnesses.

FAYETTE WILLIAM KEELER. [I.S.]
